UNITED STATES PATENT OFFICE

110,513

DESIGN FOR A BATHROOM TUB STOOL

George B. Bentz, New York, N. Y.

Application April 6, 1938, Serial No. 76,334

Term of patent 14 years

To all whom it may concern:

Be it known that I, George B. Bentz, a citizen of the United States, residing at New York, in the county of New York and State of New York, have invented a new, original, and ornamental Design for Bathroom Tub Stools, of which the following is a specification, reference being had to the accompanying drawing, forming part thereof, said design being a continuation in part of my prior application D—73,982, filed December 30, 1937.

Fig. 1 is a perspective view of a bathroom tub stool, showing my design.

Figs. 2 and 3 are side elevations looking in directions at right angles to each other.

The characteristic feature of the design is the novel contour of the legs, said legs being relatively wide at their lower portions and gradually narrowed toward their upper portions, as shown.

I claim:

The ornamental design for a bathroom tub stool, as shown and described.

GEORGE B. BENTZ.
